BELLY BOARD FOR WATER OR SNOW SKIMMING
AND THE LIKE

Robert S. Crabb, 332 6th St., Manhattan Beach,
Calif. 90266

Filed Sept. 2, 1966, Ser. No. 3,702

Term of patent 14 years

(Cl. D71—1)

FIG. 1.

FIG. 2.

FIG. 3.

FIG. 4.

FIG. 5.

FIGURE 1 is a top plan view of my new design for a belly board for water or snow skimming and the like;

I claim:

The ornamental design for a belly board for water or snow skimming and the like, as shown.
